UNITED STATES PATENT OFFICE.

HERBERT W. WOLFF, OF ST. LOUIS, MISSOURI, ASSIGNOR TO AMERICAN CAR & FOUNDRY COMPANY, OF ST. LOUIS, MISSOURI, A CORPORATION OF NEW JERSEY.

DOOR-OPERATING MECHANISM.

No. 834,789.

Specification of Letters Patent.

Patented Oct. 30, 1906.

Application filed March 31, 1906. Serial No. 309,200.

To all whom it may concern:

Be it known that I, HERBERT W. WOLFF, a citizen of the United States, residing at St. Louis, Missouri, have invented a certain new and useful Improvement in Door-Operating Mechanism, of which the following is a full, clear, and exact description, such as will enable others skilled in the art to which it appertains to make and use the same, reference being had to the accompanying drawings, forming part of this specification, in which—

Figure 1 is a side elevation of a portion of a car provided with my improved door-operating mechanism. Fig. 2 is a sectional view taken on the line 2 2 of Fig. 1, and Fig. 3 is a detail view showing the construction of the cage in which the sheave is mounted.

This invention relates to cars, and particularly to that type of cars having hopper-bottoms provided with doors which are opened to dump the contents of the car.

The object of my invention is to provide a door-operating mechanism consisting of a novel form of equalizing device, and in the preferred embodiment of my invention said device comprises a flexible member connected at its ends to the doors of the hopper and riding freely over a member which is moved upwardly to close the doors. As said flexible member rides freely on said actuated member, any inequality in the movements of the doors will be compensated for and both doors of the hopper will be closed positively. The member over which the flexible member passes preferably consists of a sheave that is connected to one end of an operating-chain, which may have its other end fastened to a winding-shaft.

The manner of connecting the sheave to its operating-chain also forms one of the novel features of my invention, said sheave being loosely mounted in a cage that is fastened to the operating-chain. The cage is of substantially yoke form and is provided in its side walls with inverted-L-shaped slots, the lower ends of which form bearings for the journals of the sheave. The sheave is retained in its cage without the aid of a rivet or fastening device, thereby reducing the cost of manufacture and enabling a new sheave to be placed in the cage when the old one has become worn or broken with very little trouble.

Referring to the drawings, which represent

the preferred form of my invention, 1 designates built-up center sills, and 2 designates one side of the car to which the outside hopper-sheet 3 is fastened. The inside hopper-sheet 4 is connected to one of the center sills, and the doors 5 for the hopper consist of plates which are strengthened by angles 6 and 7, connected to the sides and ends of the sheets, said doors being hinged at 8 to the end sheets of the hopper.

In the preferred embodiment of my invention the car is provided with a hopper on each side of the center sills, and the doors of one hopper are connected to the corresponding doors of the other hopper by members which I have herein shown as Z-bars 9, fastened to the outside faces of the doors, the said Z-bars being deflected downwardly from points adjacent their outer ends and brackets or angles 10 being provided for connecting the same to the inner end portions of the doors.

A flexible chain or cable 11 is connected at its opposite ends to the intermediate portions of the Z-bars 9, and said chain rides freely over a sheave 12, mounted in a yoke-shaped cage 13, which is connected to one end of an operating-chain 14, that passes over a sheave 15 and is connected to a winding-shaft 16. The sheave 15 is mounted on a shaft 17, carried by the center sills, and the winding-shaft is rotatably mounted in bearings 18, fastened to the center sills, and its end portions are mounted in bearings 19, carried by plates 20, that are connected to the sides of the car. At one end of said winding-shaft is a squared portion to receive a wrench or other suitable actuating device, and said shaft is also provided with a ratchet 21, that is engaged by a pivotally-mounted pawl 22 for preventing retrograde movement of said winding-shaft, said pawl being carried by a housing 23, which is connected to the plate 20, and the pawl being locked in operative position by a pivotally-mounted stop 24. The yoke-shaped cage 13 is provided in its side walls with inverted-L-shaped slots 25, and the sheave 12 is placed in said cage by inserting the journals thereof into the horizontal portion of the slots and then allowing the sheave to drop downwardly, so that the bottom of the vertical portions of the slots will act as bearings for the journals of the sheave.

105

When the sheave is in operative position and the equalizing-chain 11 is riding on the same, it will be impossible for said sheave to be displaced; but by removing said chain the sheave can easily be removed from its cage.

It will thus be seen that I have produced a construction in which the sheave is retained in its cage without the aid of a rivet or other fastening device, thereby reducing the cost of manufacture of the door-operating mechanism and enabling the sheave to be replaced in case of breakage or wear with very little trouble. As the chain 11 rides freely on the sheave 12, it acts as an equalizing device to compensate for any inequalities in the movements of the doors and insures both doors of each hopper being closed positively.

While I have herein shown my improved door-operating mechanism as being applied to a car provided with a hopper on each side of the center sills of the car and having the doors of the hoppers connected by members to which the ends of the equalizing-chain are connected, it will of course be understood that my invention is not limited to this exact construction, as the equalizing device could be used for operating only a single pair of doors.

Having thus described my invention, what I claim as new, and desire to secure by Letters Patent, is—

1. A car provided with a pair of doors, an equalizing device comprising a flexible member connected to said doors, and an actuated member on which said flexible member rides freely, thereby permitting said flexible member to travel over said actuated member; substantially as described.

2. A car provided with a pair of doors, an equalizing device comprising a flexible member connected at its opposite ends to said doors, a member on which said flexible member rides freely whereby said flexible member is permitted to travel over said member, and means for raising said member to close said doors; substantially as described.

3. A car provided with a pair of doors, a

flexible member connected to said doors, a sheave on which said member rides freely, and an actuating member to which said sheave is connected; substantially as described.

4. A car provided with a pair of doors, a flexible member connected to said doors, a sheave on which said member is movably mounted, a chain to which said sheave is connected, and a winding-shaft to which said chain is connected; substantially as described.

5. A car provided with a pair of doors, a flexible member connected to said doors, a device on which said flexible member rides freely, an actuating chain or cable to which said device is connected, and a sheave over which said chain passes; substantially as described.

6. A car provided with a pair of doors, a flexible member connected to said doors, a sheave on which said flexible member rides freely, a cage provided with open-ended slots which form bearings for the journals of said sheave, and an actuating-chain to which said cage is connected; substantially as described.

7. A car provided with hoppers on each side of its center sills, a pair of doors for each hopper, transversely-extending members connected to the corresponding doors of each hopper, a flexible member connected to said transversely-extending members, a sheave on which said flexible member rides freely, an actuating-chain to which said sheave is connected, and a sheave carried by the center sills of the car and having said actuating-chain riding thereon; substantially as described.

In testimony whereof I hereunto affix my signature, in the presence of two witnesses, this 28th day of March, 1906.

HERBERT W. WOLFF.
